J. M. ANDREWS

CINEMATOGRAPHY

Filed Nov. 19, 1921

UNITED STATES PATENT OFFICE.

JARVIS M. ANDREWS, OF WOLLASTON, MASSACHUSETTS, ASSIGNOR, BY MESNE ASSIGNMENTS, TO TECHNICOLOR MOTION PICTURE CORPORATION, OF BOSTON, MASSACHUSETTS, A CORPORATION OF MAINE.

CINEMATOGRAPHY.

Application filed November 19, 1921. Serial No. 516,357.

To all whom it may concern:

Be it known that I, JARVIS M. ANDREWS, citizen of the United States of America, and resident of Wollaston, in the county of Norfolk and State of Massachusetts, have invented new and useful Improvements in Cinematography, of which the following is a specification.

This invention relates to the art of cinematography and more particularly to an etching process and apparatus for producing films on which the images are in the form of reliefs. Such films are useful in reproducing scenes either in black-and-white or in color. In color reproduction the images are formed in complementary series and sets, each series representing one color aspect of the scene and each set (comprising one image in each series) together being adapted to produce a picture representative of the scene more or less accurately in natural colors. The complementary images may be stained or otherwise colored and then employed in various ways. For example, they may be used as matrices to transfer upon other film by imbibition; they may be separately projected upon a screen in registry in an additive process; or they may be superposed in registry and projected upon a screen in a subtractive process. When superposed they are preferably joined together as, for example, according to the disclosure in copending application of Troland and Ball, Serial No. 500,842, filed September 15, 1921.

The images may be converted into reliefs in various ways. In certain methods, which may be designated indirect relief methods, the films are exposed from the emulsion side and the exposed emulsion is etched away after the unexposed emulsion has been hardened to withstand the etching process, the unexposed emulsion being left on the film in the form of reliefs which are approximately the counterparts of the exposed portions of the emulsions. In other methods, which may be designated direct relief methods, the films are exposed through the back and the unexposed emulsion is etched away after the exposed emulsion has been

hardened, the exposed emulsion being left in the form of reliefs.

In the production of still pictures in relief form the etching has been effected by bathing the plates or films in hot water. While this method is satisfactory for single pictures such as employed in the still picture art, it is unsatisfactory in the production of cinematographic films. For example, if the film be continuously fed lengthwise through a tank of etching solution, as cinematographic films are customarily fed through developing tanks and the like, streaks frequently form on the film parallel to its direction of movement through the solution, i. e. lengthwise of the film. Furthermore, the etching is too slow, particularly if it is to be effected at a stage succeeding the developing and hardening of the emulsion in the same continuous process. Moreover, an excessive amount of etching solution is required to effect even fairly clean etching, it being necessary continuously to replenish the solution; and although the solution comprises only water the cost of heating water in sufficient quantity is commercially prohibitive in the aforesaid tank method.

Objects of the patent invention are to provide an improved method and apparatus for etching cinematographic films whereby the etching process may be performed more rapidly and cheaply and whereby the images may be etched more sharply and cleanly and with less tendency toward streaking and other imperfections.

The invention involves etching a film, after it has been conditioned for the etching process, by flowing etching liquid along the surface of the film, the film preferably being continuously advanced in the direction opposite to the flow of liquid so that it continuously passes to and from the stream, each area of the film progressively coming into contact with fresher liquid if fed counter to the stream. While the etching stream may be directed along a trough or tube through which the film is being fed it is preferably flowed along the surface of the film in a thin unconfined stream just

2

deep enough thoroughly to cover the film. This can best be accomplished by advancing the film along a path a part of which extends upwardly, either vertically or in 5 some direction other than horizontal, and causing the stream to run downwardly by gravity along the upward part of the film, that is the part advancing along the aforesaid upwardly extending part of the film 10 path. If the amount of etching liquid is properly regulated the stream will cover the film from edge to edge without leaving the film, especially if the film extends vertically or nearly so.

15 While the etching may be effected solely by a stream as aforesaid it is preferably first passed through a body of etching liquid to soften that part of the emulsion to be etched away and to start the etching action. 20 The extent to which the etching process advances in the body of liquid may be varied widely, but in any event it is completed by the aforesaid stream. When employing such a body of liquid the film is preferably fed 25 upwardly from the surface of the body directly into and through the aforesaid stream, the stream flowing downwardly along the film into the body of liquid. The stream thus replenishes the body of 30 liquid which preferably overflows from the bottom at the same rate as it is replenished. Incidentally, the stream carries any matter floating on the surface of said body away from the place where the 35 film emerges from the body, inasmuch as the stream tends to spread away from the film at said surface, whereby the floating matter is prevented from adhering to the film.

40 The aforesaid stream of liquid is agitated by its flow and this facilitates and improves the etching action. This agitation is accentuated by the film sprocket holes which tend to deflect the stream obliquely inwardly toward the center of the film.

45 After the film passes through the liquid stream the liquid superficially adhering to the film is preferably blown off in a direction both transversely and longitudinally oblique to the film, that is in a direction 50 which is oblique to both the transverse and longitudinal dimensions of the film, this being peculiarly effective in thoroughly removing the superficial liquid without streaking the film, whereas an air jet which is 55 oblique only transversely or only longitudinally of the film is ineffective thoroughly to remove the liquid and at the same time avoid streaks. The air is preferably directed to the film by an elongate nozzle or opening 60 extending substantially across the film, the opening preferably being adjustable to vary the obliquity of the jet relatively to the surface of the film.

65 The aforesaid stream of liquid is preferably directed upon the film by nozzles, that

is outlet orifices, located at the edges of the film; and in the case of double films or double-coated films the same orifices are preferably arranged to direct the stream partly to one side and partly to the other 70 side of the film.

For the purpose of illustration one concrete embodiment of the invention is shown in the accompanying drawings, in which,—

75 Fig. 1 is an elevational view;
Fig. 2 is a section on line 2—2 of Fig. 1;
Fig. 3 is a section on line 3—3 of Fig. 2;
Fig. 4 is a section on line 4—4 of Fig. 2;
Fig. 5 is a face view of one of the liquid 80 nozzles; and

Fig. 6 is a section on line 6—6 of Fig. 2.

The particular embodiment of the invention chosen for the purpose of illustration is shown as applied to apparatus for continuously developing, bleaching and fixing cinematographic films. Such apparatus ordinarily comprises a series of tanks through which the film is continuously fed in succession. In Fig. 1 two such tanks are shown at 1 and 2, the others to the right being omitted. The film enters tank 1 over rollers 3, thence passes downwardly around roller 4, thence upwardly over roller 5, thence downwardly in tank 2 over roller 6, and thence upwardly to roller 7 where it passes to the left into a drying chamber or to other film-treating apparatus. According to the present invention the tank 1 may be a wash tank and tank 2 an etching tank, the latter tank being provided with an overflow 8 which communicates with the tank 90 at the bottom and overflows at 9.

95 The liquid nozzle above referred to preferably comprises an orifice 10 located at the edge of the film so as to direct the liquid onto the film from the side. When the film is double-coated and is to be etched on both sides, the orifice is preferably so positioned that it is bisected by the plane of the film, as shown in Fig. 5, whereby the liquid is 100 directed to both sides of the film from the same orifice. In order to position the film relatively to the orifice, guides are provided adjacent the orifice and in the preferred embodiment illustrated in the drawings 105 these guides are mounted upon and formed integrally with the nozzle, the guides being in the form of flanges 11 and 12 forming a channel 13 therebetween to receive the film. These flanges are preferably shaped and positioned to bear upon the film only at points 14 and 15, thereby to center the film 110 relatively to the orifice without engaging the film throughout a very large area. The flanges 11 and 12 preferably extend only to the sprocket holes of the film, the position of which is indicated at 16 in Fig. 2 so as not to rub against the image-bearing portion of the film. By inclining the nozzle 115 relative to the path of the film, as shown 120

125

in Fig. 5, the ends of the flanges serve as the bearings for guiding the film and the orifices are inclined to the path of the film so that an adequate quantity of water is directed to both sides of the film even though the film is somewhat warped and therefore does not lie wholly in the plane defined by the bearing edges 14 and 15. In the particular embodiment illustrated, identical nozzles are provided on opposite sides of the film, and they connect through branched ducts 17 and 18 with a common supply pipe 19.

The nozzles 10 are preferably located directly above the etching tank 2 so that the film extends substantially vertically from the tank to the nozzles, especially if the film is to be etched on both sides. The distance of the nozzles above the tank depends upon the rate of liquid flow, its temperature, the rate of film travel, and the extent to which the etching progresses in the tank 2, but in any event the distance is sufficiently great so that the film is completely etched by the time it reaches the nozzles.

A suitable etching liquid comprises water at a temperature of about 120° F. the water being supplied at such a rate that a stream flows down each side of the film from the nozzles to the tank 2, the stream being relatively thin or shallow but extending the full width of the film. With the rate of flow properly adjusted both sides of the film can be fully covered throughout the entire distance between the nozzle and the tank without any of the liquid overflowing at the edges of the film.

In the illustrated embodiment the film passes between opposed air nozzles 20 shortly after passing between the liquid nozzles 10. The preferred construction of the air nozzles comprises two tubular members extending in parallel relationship along opposite sides of the film, and joined at 21 with the two branches 22 of larger tube 23, the end of which is formed as shown in Figs. 2 and 4 to fit the ends of the tubes 20. On the inner side of the tubes 20 are longitudinal slots 24 facing the opposite sides of the film. Fitting within the tubes 20 with a snug sliding fit, are tubes 25 which are provided with narrow longitudinal slots 26. The tubes 25 are open at their lower ends (Fig. 2) and closed at their upper ends, the upper ends being provided with handles 27 which project beyond the open ends of the outer tubes 20. By means of handles 27 the inner tubes may be rotated to adjust the direction of slots 26, thereby to adjust the angularity of the jet of air from the nozzles to the film.

An improved feature of the invention involves the oblique arrangement of the air nozzles relatively to the film, the nozzles

being oblique relatively to both the transverse and longitudinal dimensions of the film, the preferred degree of angularity being illustrated in Fig. 2. In addition to this oblique disposition of the tubes the slots 26 are preferably positioned by means of the handles 27 so that the air jets are directed downwardly and to the left (Fig. 2). With this arrangement substantially all of the superficial liquid is blown off the film and at the same time the streaks on the film, caused by prior air nozzles, are avoided. If the tubes 20 extended horizontally parallel to the transverse dimensions of the film so as to blow the water downwardly along the film, there would be a tendency for streaks longitudinally of the film to appear after the film is dry. If the air nozzles were located at one edge of the film to blow horizontally across the film, there would be a tendency toward unequal removal of the superficial liquid and in some cases a considerable amount of the liquid might not be blown off, especially near the edge of the film opposite to the air nozzles.

The operation of the apparatus is as follows: The film is fed continuously through the apparatus as aforesaid. As the film passes through the tank 2, the gelatin to be etched away is softened and may be etched away to some extent, this tank being filled with water at approximately 120° F. As the film passes upwardly from the surface of the body of liquid in tank 2 to the nozzles 10, both sides of the film are subjected to the action of a rapidly flowing stream of hot water. This stream of water is naturally agitated by its own flow and is further agitated by the sprocket holes which tend to divert the water inwardly from both sides toward the center thereby keeping it thoroughly stirred. The result is that the soft gelatin is rapidly carried away and the film, after passing nozzles 10, is entirely cleansed of soft gelatin leaving the hard gelatin in sharp relief. Inasmuch as the marginal portions of the film are never exposed, the gelatin on the margins entirely washes away leaving perfectly clean celluloid outside the sprocket holes. After the film passes nozzles 10 it passes between nozzles 20 where the liquid superficially adhering to the film is blown off so that the film may be quickly dried when subsequently passed through a drying chamber. The tank 2 may be continuously replenished with hot water by a pipe opening thereinto either at the top or bottom or any intermediate position, but ordinarily the water flowing downwardly along the film from the nozzles 10 is sufficient for this purpose.

By virtue of the above-described method and apparatus, the film is etched rapidly and cleanly, and the amount of hot water

required for the purpose is only a small fraction of the amount required by other known processes.

No claim is made to the air nozzle per se, the same being claimed in application Serial No. 58,287, filed Sept. 24, 1925, which is a division of this application.

I claim:

1. The art of forming relief cinematographic films which comprises conditioning a film for the etching process and then flowing etching liquid along the surface of the film.

2. The art of forming relief cinematographic films which comprises conditioning a film for the etching process, continuously advancing the film in one direction, and flowing an etching liquid along the surface of the film in the opposite direction.

3. The art of forming relief cinematographic films which comprises conditioning a film for the etching process and then flowing a thin unconfined stream of etching liquid along the surface of the film.

4. The art of forming relief cinematographic films which comprises conditioning a film for the etching process, positioning the film so that it extends downward longitudinally, and directing a stream of etching liquid upon the film so that it runs downwardly along the surface of the film.

5. The art of forming relief cinematographic films which comprises conditioning a film for the etching process, continuously advancing the film along a path a part of which extends upwardly, and directing a stream of etching liquid upon the film so that it runs downwardly along the surface of the film as the latter advances along the upward part of said path, the liquid being supplied in such quantity and manner as to form a stream which is continuous across the central image-bearing width of the film.

6. The art of forming relief cinematographic films which comprises conditioning a film for the etching process, advancing the film through a body of etching liquid and thence upwardly from said body, and flowing etching liquid downwardly along the surface of the film above said body.

7. The art of forming relief cinematographic films which comprises conditioning a film for the etching process, advancing the film through a body of etching liquid and thence upwardly from said body, and flowing etching liquid from a location above the level of said body downwardly along the surface of the film to said body, the liquid being supplied in such quantity and manner as to form a stream which is continuous across the central image-bearing width of the film.

8. The art of forming relief cinematographic films which comprises conditioning a film for the etching process, and flow-

ing etching liquid upon the film from opposite edges to cause a stream which is continuous across the central image-bearing width of the film to flow downwardly therealong.

9. The art of forming relief cinematographic films which comprises conditioning a film for the etching process, advancing the film along a path a part of which extends upwardly, directing a stream of etching liquid upon the film so that it runs downwardly along the surface of the film as the latter advances along the upward part of said path, and blowing the superficial liquid from the film after it passes through said stream.

10. The art of forming relief cinematographic films which comprises conditioning a film for the etching process, advancing the film along a path a part of which extends upwardly, directing a stream of etching liquid upon the film so that it runs downwardly along the surface of the film as the latter advances along the upward part of said path, and blowing the superficial liquid from the film in a direction both transversely and longitudinally oblique to the film.

11. The art of forming relief cinematographic films, the combination of means for continuously advancing a film along a path a part of which extends upwardly, a liquid nozzle located adjacent the upward part of said path for directing a stream of etching liquid upon the film so that it runs downwardly therealong, and an air nozzle having an elongate outlet extending approximately parallel to the film in a direction oblique to the direction of film advance for blowing off the superficial liquid after the film passes through said stream.

12. In the art of forming cinematographic films, the combination of means for continuously advancing a film along a predetermined path, and a branched nozzle having openings directed toward the film on opposite edges thereof.

13. In the art of forming cinematographic films, the combination of means for continuously advancing a film along a predetermined path, and a branched nozzle having openings directed toward opposite edges of the film.

14. In the art of forming cinematographic films, the combination of means for continuously advancing a film along a predetermined path, and a branched nozzle having openings directed toward opposite edges of the film, the openings being disposed in part on one side of the plane of the film and in part on the other side of said plane.

15. In the art of forming cinematographic films, the combination of means for continuously advancing a film along a predetermined path, and means having fluid

70

85

openings directed toward the edges of the film, the openings being positioned in the plane of the film so as to be intersected thereby.

5 16. In the art of forming cinematographic films, the combination of means for continuously advancing a film along a path, a liquid nozzle for directing a stream of liquid upon the film so that it runs downward thereon, and an elongate nozzle extending approximately parallel to the film but obliquely to the path of the latter, said second mentioned nozzle having an outlet adapted to be directed in a direction transverse of the film

10 and counter to the direction of film advance.

15 17. In the art of forming cinematographic films, the combination of means for continuously advancing a film along a path, a part of which extends upwardly, a liquid nozzle for directing a stream of etching liquid upon the film so that it runs downwardly therealong, and an elongate nozzle extending along one side of the film, the outlet of said last mentioned nozzle being angularly related to the film and being angularly adjustable relatively thereto.

20 18. In the art of forming cinematographic films, the combination of means for advancing a film along a predetermined path, means for flowing a sheet of liquid thereon, and a tubular nozzle extending along one side of the film and having an outlet at one side thereof and being rotatable to adjust the position of the outlet relative to the film.

25 19. In the art of forming cinematographic films, the combination of means for continuously advancing a film along a predetermined path, means for causing a sheet of liquid to flow longitudinally thereof, and a tubular nozzle extending along one side of the film and having a longitudinal slot along one side and being rotatable about its axis to adjust the angularity of the slot relative to the film.

30 20. In the art of forming cinematographic films, the combination of means for continuously advancing a film along a predetermined path, means for causing a sheet of liquid to flow thereon, and means for directing fluid upon said film at a point beyond said first mentioned means in the direction of motion of the film including a nozzle comprising two telescoped tubes rotatable relative to each other, one tube having a wide slot along one side and the other having a narrower slot movable transversely of the wide slot upon relative rotation of the tubes.

35 21. In the art of forming cinematographic films, the combination of means for continuously advancing a film along a predetermined path, and a branched nozzle having openings directed toward the film on oppo-

site sides thereof and discharging in a direction parallel to the surface of said film.

40 22. In the art of forming cinematographic films, the combination of means for continuously advancing a film along a predetermined path, and a branched nozzle having openings directed toward the film on opposite sides thereof and discharging in a direction transverse to the path of said film but parallel to the plane thereof.

45 23. In the art of forming cinematographic films, the combination of means for continuously advancing a film along a predetermined path, and a branched nozzle with openings arranged outside the lateral limits of said film and directed toward each other.

50 24. In the art of forming cinematographic films, the combination of means for continuously advancing a film along a predetermined path, and means discharging thereon a stream divided by said film.

55 25. In the art of forming cinematographic films, the combination of means for continuously advancing a film along a predetermined path, and means discharging thereon a stream bisected by said film.

60 26. In the art of forming cinematographic films, the combination of means for continuously advancing a film along a predetermined path, and means discharging thereon a stream in a direction substantially parallel to the plane of said film and transverse to its path.

65 27. In the art of forming cinematographic films, the combination of means for continuously advancing a film along a predetermined path, means for discharging thereon a stream divided by said film, and guiding means cooperating only with the edges of said film at points at opposite sides of said discharging means.

70 28. In the art of forming cinematographic films, the combination of means for continuously advancing a film along a predetermined path, and means for guiding said film and discharging thereon a stream divided by said film including a nozzle having a discharge orifice cut by the plane of said film and guiding means for said film at opposite sides of said discharge orifice.

75 29. The art of forming a series of relief pictures on an elongate photographic film by rendering the exposed and unexposed portions differentially soluble and flowing hot water or other etching liquid along the surface of the film, characterized in that the film is fed longitudinally a considerable distance along an upwardly extending path and the liquid is flowed upon the film from an orifice in such close juxtaposition to the film that a stream of liquid flows downwardly along the face of the film with little if any overflow from the film until the stream reaches the lower end of said path.

30. The art according to claim 29 further characterized in that the etching liquid is flowed upon the film from its opposite edges so as to spread entirely across both sides of the film.

31. Apparatus for subjecting a moving film to the action of a fluid characterized by

a nozzle in close juxtaposition to the path of the film and means associated with the nozzle for guiding the film past the nozzle in predetermined relationship thereto.

Signed by me at Boston, Massachusetts, this 5th day of November 1921.

JARVIS M. ANDREWS.
